Dec. 1257.

Louis Meyer, of St. Louis Missouri.
Letters Patent No 1257, dated June 19, 1860.

The schedule referred to in these Letters Patent, and making part of the same
all whom it may concern:

Be it known that I, Louis Meyer, of St. Louis, in the

2

Des. 1257

County of St Louis and State of Missouri, have produced a new ornamental design for Stoves, and I do hereby declare that the following is a full, clear and exact description of the same, reference being had to the accompanying drawings forming a part of this Specification.

The drawing represents a front view of my new design for Stove.

The stove in its horizontal section is cylindrical.

The base A, is ornamented by mouldings a, b, and circular openings c, which have beads d, formed all around them as shown.

The body B, has an ornament C, of the character represented, projecting from each side, and is further beautified by circular openings e, f, which have beads g, all round them, and by mouldings h, i, and by a beaded door j, k, and an ornament l, of the character represented in the drawing.

The cap D, of the Stove has mouldings m, n, o, formed on it, and is further beautified by being partly made of open lattice work of the character represented in the drawing.

The Stove design described and represented in the drawing is simple and neat, and quite ornamental.

What I claim and desire to secure by Letters Patent, is the ornamental design for a parlor stove, herein described and represented.
